UNITED STATES PATENT OFFICE.

WILLIAM ANGLE, OF WELSH RUN, PENNSYLVANIA.

MAIL-BAG CATCHER.

SPECIFICATION forming part of Letters Patent No. 292,975, dated February 5, 1884.

Application filed November 26, 1883. (No model.)

To all whom it may concern:

Be it known that I, WILLIAM ANGLE, a citizen of the United States, and a resident of Welsh Run, in the county of Franklin and State of Pennsylvania, have invented certain new and useful Improvements in Mail-Bag Catchers; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved mail-bag catcher, showing it in position for catching the mail-bag. Fig. 2 is a similar view, showing the position when the bag is caught; and Fig. 3 is a horizontal section of the catcher.

Similar letters of reference indicate corresponding parts in all the figures.

My invention has relation to mail-bag catchers for railroad-cars, having means for holding the bag after it has been caught; and it consists in the improved construction and combination of parts of the same, as herein-after more fully described and claimed.

In the accompanying drawings, the letter A indicates the side of a car, which is provided with two bails or bearings, B B, in which the ends of a bar, C, are journaled, which bars form the inner side of a casing, D, in which the mechanism for holding the bag is placed, and which has the catcher-arm E projecting obliquely outward and forward from the outer rear corner. A bar, F, projects from the inner side of the casing and passes through the side of the car, serving to raise the catcher when a bag is to be caught, the catcher hanging down upon the side of the car when not in use. A curved arm, G, is pivoted at its inner end inside the casing and projects with its outer end through the outer side of the casing, sliding in a slot, H, in the said side, and is shaped curving rearward in such a manner that its outer end will bear against the inner edge of the catcher-arm when the curved arm is brought rearward. A spring, I, bears against the back of the said arm, forcing it rearward, and the inner end of the arm forms a disk, J, the center of which is upon the pivot K of the arm, which disk has a notch, L, at its rear edge, which notch may be engaged by a lug or pro-

jection, M, upon a trigger, N, pivoted at its inner end inside the casing, and projecting with its outer end through a slot, O, in the outer side of the casing in the inner corner of the fork formed by the casing and the catcher-arm, and forced forward by a spring, P, so that the lug upon the trigger will catch and engage the notch in the edge of the disk when the curved arm has been drawn forward, holding it in that position. It will now be seen that when the catcher catches a mail-bag, when the curved arm and the trigger are thus set, the mail-bag will strike the trigger as it is forced into the corner of the catcher, pushing the trigger back, which releases the curved arm, which then will spring rearward, clasping the bag and holding it until it is released, when the catcher may be set for the next bag, &c.

Having thus described my invention, I claim and desire to secure by Letters Patent of the United States—

1. A mail-bag catcher consisting of a catcher-arm, a curved clasping-arm having means for forcing it rearward, clasping the bag from the front, and a trigger at the inner corner of the catcher-arm, releasing the curved clasping-arm when struck, as and for the purpose shown and set forth.

2. The combination of a casing having trunnions at its inner corners and an inwardly-projecting arm upon its inner side, an outwardly and forwardly projecting catcher-arm attached to the outer rear corner of the casing, a rearwardly-curved clasping-arm pivoted at its inner end inside the casing, projecting through its outer side, and forming a disk upon its inner end, having a notch, a spring bearing against the back of the clasping-arm and forcing it rearward, a trigger projecting with its outer end through the outer side of the casing in the fork formed by the catcher-arm and the casing, and having a lug engaging the notch in the disk upon the end of the clasping-arm, and a spring forcing the trigger forward, all constructed to operate as and for the purpose shown and set forth.

In testimony that I claim the foregoing as my own I have hereunto affixed my signature in presence of two witnesses.

WILLIAM ANGLE.
